US0D1091566S

(12) **United States Design Patent** (10) **Patent No.:** **US D1,091,566 S**
(45) **Date of Patent:** **** Sep. 2, 2025**

(54) **DISPLAY SCREEN WITH GRAPHICAL USER INTERFACE**

(71) Applicant: **Google LLC**, Mountain View, CA (US)

(72) Inventors: **Nobuhiro Makida**, Tokyo (JP); **Holly Thai**, Mountain View, CA (US)

(73) Assignee: **GOOGLE LLC**, Mountain View, CA (US)

(**) Term: **15 Years**

(21) Appl. No.: **29/823,164**

(22) Filed: **Jan. 14, 2022**

Related U.S. Application Data

(62) Division of application No. 29/667,084, filed on Oct. 18, 2018, now Pat. No. Des. 945,435, which is a division of application No. 29/563,177, filed on May 3, 2016, now Pat. No. Des. 835,133, which is a division of application No. 29/436,020, filed on Oct. 31, 2012, now Pat. No. Des. 756,383.

CLAIM

The ornamental design for a display screen with graphical user interface, as shown and described.

DESCRIPTION

The sole FIGURE is a front view of a display screen with graphical user interface showing our new design.

The broken line showing of a display screen with graphical user interface is included for the purpose of illustrating portions of the article and forms no part of the claimed design.
